UNITED STATES PATENT OFFICE.

OTTO J. GROEHN, OF DETROIT, MICHIGAN, ASSIGNOR TO BRISCOE MANUFACTURING COMPANY, OF DETROIT, MICHIGAN, A CORPORATION OF MICHIGAN.

MACHINE FOR FLANGING SHEET METAL.

1,112,696.

Specification of Letters Patent.

Patented Oct. 6, 1914.

Application filed October 30, 1912. Serial No. 728,685.

To all whom it may concern:

Be it known that I, OTTO J. GROEHN, a citizen of the United States of America, residing at Detroit, in the county of Wayne 5 and State of Michigan, have invented certain new and useful Improvements in Machines for Flanging Sheet Metal, of which the following is a specification, reference being had therein to the accompanying drawings.

The invention relates to machines for flanging sheet metal, and it is the object of the invention to provide means for forming oppositely-bent, hooked flanges upon the opposite edges of metallic strips. It is a further object to adapt the machine for operating upon strips of different widths.

With these objects in view the invention consists in the construction as hereinafter set forth.

In the drawings: Figure 1 is a plan view of the machine; Fig. 2 is an end elevation thereof; Fig. 3 is a perspective view of the work formed by the machine; Figs. 4, 5 and 25 6 are cross sections showing the blank in the several stages of formation; and Fig. 7 is a section in the plane of one of the rolls.

A is the frame or bed, upon which is mounted the parallel side frames B and C. 30 Extending transversely between these side frames and journaled therein, are series of cross shafts D E E' and F F'. The shafts E E' F F' are arranged in pairs, and are formed of telescopically-engaging sections 35 splined to each other.

G H are coöperating forming rolls upon one of the telescopic sections of each of the shafts E E'; and G' H' are reversely arranged forming rolls on the corresponding 40 sections of said shafts E and E'. I J and I' J' are forming rolls mounted in like manner upon the telescopic sections of the shafts F and F', the arrangement being such that in the passing of a strip into engagement 45 with said forming rolls, the opposite edges of said strip will be flanged in opposite directions.

To permit of operating upon strips of varying widths, one of the side frames, such 50 as B, is laterally adjustable; and to this end is secured by clamping bolts K, and is held in parallelism to the frame C by guides L. In adjusting the frame, the sections of the shafts E E' F F' journaled therein, together

with the forming rolls G' H' I' J', will be 55 carried and adjusted in relation to the opposite forming rolls G H I J. Endwise displacement of the shaft sections with reference to their respective frames is prevented by collars L' upon opposite sides of the 60 journal bearings.

M M' are return-bending or hook-forming rolls in alinement with the rolls G H and I J; and N N' are corresponding return-bending or hook-forming rolls in alinement with 65 the rolls G' H' I' J'. These hook-forming rolls are arranged in horizontal planes, and are respectively carried by bearings O and P on the side frames B and C.

The various rolls are driven by a suitable 70 drive train, comprising the intermeshing gear-wheels Q R S T U V and W X. The gear-wheels V and X drive shafts respectively upon the frames B and C, which are connected by bevel gear-wheels Y and Y' 75 respectively with the vertical shafts Z and Z', on which the rolls M and N are mounted. With the construction as described, it will be understood that the forming rolls G H I J M N are in alinement with each other, and in 80 like manner the rolls G' H' I' J' M' N' are in alinement; but that the two series of rolls are relatively adjustable. Thus whenever the frame B is laterally adjusted, it will 85 carry with it the series of rolls mounted thereon and thus the two series may be set to correspond to the width of any strip of metal to be formed.

In operation the rolls G H G' H' initiate the bending of the edges of the strips; the 90 rolls I J I' J' complete a right-angle bend; and the rolls M M' N N' effect the return bending of the flange, the completed product having reverse bent flanges, as shown in Fig. 3.

What I claim as my invention is:

1. A machine for flanging sheet metal strips, comprising a bed, a side frame mounted thereon, a second side frame, laterally adjustably mounted upon the opposite side of 100 said bed, guiding means for holding said frame in parallelism with the first-mentioned frame in each position of adjustment, a series of shafts formed in telescoping sections, extending between said frames, and 105 having their corresponding sections mounted in the respective frames, a series of alined forming rolls mounted on the shaft sections

of one of said frames, and a corresponding series of aligned forming rolls mounted on the shaft sections of the opposite frame.

2. In a machine for flanging the opposite edge portions of sheet metal strips, the combination with parallel frames, of cross shafts extending between said frames and formed in telescopically engaging sections held from endwise movement in their respective frames, aligned corresponding series of flanging and return-bending rolls mounted on the telescopic sections of the respective frames, one of said frames being laterally adjustable

relative to the other frame, the series of rolls of said adjustable frame being adjustable therewith as an entity, and guiding means for holding said frame in parallelism with the other frame in each position of adjustment.

In testimony whereof I affix my signature in presence of two witnesses.

OTTO J. GROEHN.
